UNITED STATES PATENT OFFICE

FREDERICK H. HOLBROOK, OF BOSTON, MASSACHUSETTS.

RAISED EMBROIDERY.

SPECIFICATION forming part of Letters Patent No. 293,877, dated February 19, 1884.

Application filed May 14, 1883. (No model.)

To all whom it may concern:

Be it known that I, FREDERICK H. HOLBROOK, of Boston, in the county of Suffolk and State of Massachusetts, have invented certain 5 Improvements in Raised Embroidery, of which the following is a specification.

My invention has for its object to provide an improved ornamental article for use in embroidery to represent raised buds or flowers; and it consists in a piece of woven silk or other textile fabric folded to form a shell or body, which, when applied to a surface to be ornamented, will stand out from said surface and constitute a raised ornament, the 15 folds of the piece being secured together prior to their attachment to the said surface, so that the piece will retain its peculiar form, as I will now proceed to describe and claim.

Of the accompanying drawings, forming a 20 part of this specification, Figure 1 represents a piece of material such as I employ in making my improved embroidery. Figs. 2, 3, and 4 represent different stages of the operation of folding. Figs. 5, 6, and 7 represent, respectively, front, back, and edge views of the completed article. Fig. 8 represents the same as applied to the surface to be ornamented.

The same letters of reference indicate the same parts in all the figures.

30 In carrying out my invention, I take a piece, *a*, of silk or other suitable fabric, which may be a waste scrap or remnant. The shape of the piece is preferably rectangular, although this is not essential. I fold the piece *a*, as shown in Fig. 2, preferably along the line *c d*, Fig. 1. I then form a series of plaits or folds, *ff*, from near the folded edge *e* to the opposite margin of the piece, making the first plaits at the center, as shown in Fig. 3, and successively forming them at opposite sides of the center, as shown in Fig. 4, until all the material is disposed of in plaits. This operation gradually bends the folded edge *e* to the oval or curved form shown in Figs. 5 and 6, and 45 also bends said edge backwardly, converting it into a marginal rim or flange, which gives the folded piece a thick and massive appearance and causes the plaits or folds to stand out in relief from the surface on which the piece

is laid. After folding, as described, I secure 50 the free ends of the folds or plaits together by stitches *i i*, or by other suitable means, so as to retain the piece in the form imparted to it by the folding operation. The article thus made is placed upon a piece of cloth or other 55 material to be ornamented, and secured thereto by suitable embroidery-stitches, which complete the design, the folded piece resembling, for example, the folded petals of a rose-bud, and the embroidery-stitches the stem and 60 other parts of the bud. (See Fig. 8.) The pieces folded and having the folds or plaits bound together, as described, may be sold as articles of manufacture for the use of slipper-manufacturers and others. The uniformity in 65 shape of the folded pieces caused by the described method of folding makes said pieces especially desirable for the ornamentation of slippers by manufacturers. The inwardly-turned folded edge *e* bearing on the surface to 70 which the piece is applied supports the folds or plaits *f* in a raised position, and prevents them from being flattened or crushed inwardly.

Heretofore a flat piece of fabric has been secured to a cloth surface, so as to form a pocket, 75 which has been stuffed with cotton to give it a raised surface, embroidery-stitches being afterward added to complete the design. Such method involves more labor and does not produce such satisfactory results as mine, the 80 cotton stuffing being flattened by use, so that the fabric supported thereby does not retain the desired form.

In some cases I prefer to finish the bud by adding thereto a calyx and stem, *s*, as shown 85 in Fig. 10, the same being stamped or embossed from a thin piece of metal and provided with prongs *s' s'*, Fig. 9, adapted to penetrate the material to which the bud is applied.

I claim—

1. The improved embroidery material composed of a piece of fabric folded, as described, to form a series of plaits, *ff*, and a marginal backwardly-turned folded edge, *e*, said plaits being secured together at their outer ends, as 95 set forth.

2. Raised embroidery composed of a piece of fabric, *a*, folded to form a series of plaits,

f, and a backwardly-turned edge, *e*, and embroidery-strokes connecting said folded piece to the surface to be ornamented, as set forth.

3. The raised embroidery, formed as described, and connected to the material to be ornamented by embroidery stitches, combined with the molded or embossed ornaments, provided with means for attachment to said material, as set forth.

In testimony whereof I have signed my name to this specification, in the presence of two subscribing witnesses, this 7th day of May, 1883.

FREDERICK H. HOLBROOK.
